FIELD CHECK FORMING MACHINE

Charles F. Rhyno and Marion L. Rhyno,
Modesto, Calif.

Application November 10, 1948, Serial No. 59,314

7 Claims. (Cl. 37—171)

1

This invention relates in general to a machine for earth working purposes; the invention being directed in particular to, and it is an object to provide, a check forming machine of novel construction and operation.

Another object of the invention is to provide a check forming machine which is tractor mounted, and operative—upon advance of the tractor—to smoothly and evenly sweep earth in opposite lateral directions to windrow said earth in relatively widely spaced relation as parallel field checks; the ground between said checks being worked by the machine to a predetermined level for use as a seed bed.

A further object of the invention is to provide a check forming machine which includes a longitudinal, wide, V blade assembly frame supported for travel with the apex foremost; there being a novel frame or mount for securing said blade assembly in connection with a tractor for pushing by the latter.

An additional object contemplates the provision of a novel adjusting or leveling arrangement for the blade assembly; the latter including elongated, forwardly converging blades which are mounted for individual power adjustment up or down, selectively, about a swivel point adjacent their forward ends.

It is also an object of the invention to provide a check forming machine which is designed for ease and economy of manufacture, and long life, with a minimum of servicing or maintenance.

A further object of the invention is to provide a practical and reliable check forming machine, and one which will be exceedingly effective for the purpose for which it is designed.

These objects are accomplished by means of such structure and relative arrangement of parts as will fully appear by a perusal of the following specification and claims.

In the drawings:

Fig. 1 is a plan view of the check forming machine as in use.

Fig. 2 is a side elevation of the machine.

Fig. 3 is a rear end view of the same.

Fig. 4 is an enlarged fragmentary plan view of the swivel connection for the forward ends of the elongated blades.

Referring now more particularly to the characters of reference on the drawings, the novel check forming machine comprises a generally horizontally disposed, U-shaped yoke or push frame 1 adapted to straddle a track type tractor, indicated generally at 2, from the front; the rear ends of said push frame 1 being journaled

2

in connection with trunnion 3 which project laterally outwardly from the track frames of said tractor. The push frame 1 is thus mounted in connection with the tractor for relative vertical adjustment. At the front, and centrally of the sides thereof, the push frame 1 is fitted with a longitudinal, forwardly projecting push beam 4, and diagonal braces 5 extend forwardly in converging relation from the front corners of the push frame to connection with the push beam 4 adjacent but short of its front end.

The above described frame assembly, including push frame 1 and push beam 4, is vertically adjustable with relation to the tractor by means of a block and tackle cable system 6 which extends at a forward and downward incline from the front of an upstanding A-frame 7 on the tractor, to the top of a unitary tripod 8 on said frame assembly ahead of the tractor; said block and tackle cable system 6 including a pull reach 9 which leads rearwardly to the back of the tractor, whence it is connected to a conventional power control unit P. With this arrangement the frame assembly can be raised or lowered, at the selection of the operator, about trunnions 3 as an axis.

At the front end thereof the check forming machine is supported by a relatively wide, transverse axis roller 10 journaled in a fork 11 which is fixed in connection with a longitudinal mounting beam 12 which extends rearwardly in overhanging relation to the front end portion of the push beam 4. At its rear end the longitudinal mounting beam 12 is pivotally connected, as at 13, to said push beam 4, and ahead of the pivot 13 there is a vertical adjustment bracket 14 by means of which the longitudinal mounting beam 12 can be set to position the front end of the push beam 4 at a predetermined working height above the ground.

The earth working elements of the machine comprise a pair of extremely elongated, longitudinal blades 15 which extend from adjacent the front end of the push beam 4 in rearwardly diverging relation on opposite sides of the tractor 2 and the frame assembly as mounted thereon. The blades 15 are disposed vertically edgewise and are formed on the face to work the earth laterally outwardly upon advance of the machine.

The blades 15 are mounted in connection with the frame assembly, comprised of push frame 1 and push beam 4, by a plurality of lateral stays 16 which extend between a longitudinal stiffening bar 17 on the back of each blade, and a corresponding point on the tractor-mounted frame as-

sembly. The stays 16 are spaced apart lengthwise of the machine, and at their outer ends are connected by vertical pivots 18 to the corresponding bar 17, and at their inner ends are connected by horizontal pivots 19 to the tractor-mounted frame assembly.

Adjacent their forward ends the blades 15 are swivelly connected to the front end of the push beam 4 by laterally inwardly projecting ears 20, through which a forwardly projecting trunnion 21 on said push beam projects in relatively loose-play relation.

As so mounted the blades 15 are each capable of up or down adjustment about their forward end portions as an axis; such adjustment being accomplished as follows:

At the rear end thereof the U-shaped push frame 1 includes, in unitary relation, an upstanding inverted U-shaped arch frame 22, and diagonal braces 23 maintain said frame 22 rigid with respect to the remainder of the tractor-mounted frame assembly.

Upstanding triangular frames 24 extend laterally from opposite sides of the arch frame 22, and said triangular frames 24 are connected, at their lower inner ends, by double swivels 25 to the lower end of the corresponding leg 26 of the arch frame 22. At their outer ends the triangular frames 24 are pivotally linked, as at 27, to the bar 17 of the adjacent blade 15.

A double acting, fluid pressure actuated power cylinder 28 is connected by a double swivel 29 to the arch frame 22 on each side adjacent the top, and thence extends laterally outwardly to pivotal connection, as at 30, with the apex of the corresponding upstanding triangular frame 24. The power cylinders 28 are independently operative at the selection of the operator of the tractor, being controlled by a valved fluid pressure system, indicated diagrammatically and in part at 31.

The rear end portions 32 of the blades 15 are initially separate elements, being attached to the remainder of the corresponding blade by detachable connection units 33. When said rear portions 32 of the blades 15 are in use, which is for the purpose of increasing the effective or working width of the machine, said rear portions 32 are stabilized by rearwardly converging tie rods 34 which pivotally connect between said portions 32, as at 35, and the rear hitch 36 of the tractor, as at 37.

The above described check forming machine is used in the following manner:

At the outset the tractor-mounted frame assembly, including push frame 1 and push beam 4, is adjusted to predetermined working position by means of the block and tackle cable system, and then the longitudinal mounting beam 12 is vertically adjusted at the bracket 14 to position the roller 10 in ground engagement. Thereafter, with advance of the machine the roller 10 maintains the front end of the tractor-mounted frame assembly at a predetermined height above ground.

The blades 15 are each adjusted to their predetermined working position by selective operation of the power cylinders 28; contraction of each such cylinder tending to raise the corresponding blade 15 for its full length and about its front end portion as an axis. In this manner the blades 15 initially, and during subsequent operations, can each be set to any desired working position.

As the machine advances along a field, the

symmetrically disposed blades 15 smoothly work a quantity of the earth from the surface of the field and sweep such earth laterally outwardly until it discharges from the rear ends of the blades 15 as a check. The machine is thus operative to form transversely spaced, parallel checks simultaneously, while smoothing the field between such checks for use as a seed bed.

For turning at the end of a field, the power cylinders 28 are first contracted, swinging the blades 15 some distance above ground, and then the cable system 6 is shortened so as to swing the tractor-mounted frame assembly, together with the blades, to an elevated point, whereby the tractor may reverse its direction of travel without said blades digging in or obstructing the operation.

The described check forming machine provides a very practical and effective implement for the intended purpose, and yet its structure is relatively simple but rugged, and requires very little servicing or maintenance.

From the foregoing description it will be readily seen that there has been produced such a device as substantially fulfills the objects of the invention, as set forth herein.

While this specification sets forth in detail the present and preferred construction of the device, still in practice such deviations from such detail may be resorted to as do not form a departure from the spirit of the invention, as defined by the appended claims.

Having thus described the invention, the following is claimed as new and useful, and upon which Letters Patent are desired:

1. A check forming machine comprising a push frame assembly yoke-like at the rear end for straddling a tractor from the front and including a forwardly projecting frame portion, an elongated V-shaped earth working blade structure including separate blades extending rearwardly from its apex on opposite sides of the push frame assembly, means pivotally connecting the front ends of the blades to said forwardly projecting portion for vertical adjustment of said blades, a plurality of longitudinally spaced, vertically swingable transverse stay bars pivotally connected between the blades and the push frame assembly, and power means connected between each blade and the push frame assembly in lift relation to said blade; such power means comprising an upstanding, generally triangular frame extending transversely between and pivotally connected to the corresponding blade and said push frame assembly, and a fluid pressure actuated power cylinder connected to the apex of said triangular frame in rocking relation thereto.

2. A check forming machine comprising a push frame assembly yoke-like at the rear end for straddling a tractor from the front and including a forwardly projecting frame portion, an elongated V-shaped earth working blade structure including separate blades extending rearwardly from its apex on opposite sides of the push frame assembly, means pivotally connecting the front ends of the blades to said forwardly projecting portion for vertical adjustment of said blades, a plurality of longitudinally spaced, vertically swingable transverse stay bars pivotally connected between the blades and the push frame assembly, an arch frame upstanding from the push frame assembly adjacent its rear end, an upstanding, generally triangular frame pivotally connected at its lower ends to and extending transversely between the push frame assembly and each blade

substantially in alignment with the arch frame, and a power device connected between the apex of each triangular frame and the arch frame to swing the former up or down.

3. A check forming machine comprising a push frame assembly yoke-like at the rear end for straddling a tractor from the front and including a forwardly projecting frame portion, an elongated V-shaped earth working blade structure including separate blades extending rearwardly from its apex on opposite sides of the push frame assembly, means pivotally connecting the front ends of the blades to said forwardly projecting portion for vertical adjustment of said blades, a plurality of longitudinally spaced, vertically swingable transverse stay bars pivotally connected between the blades and the push frame assembly, an arch frame upstanding from the push frame assembly adjacent its rear end, an upstanding, generally triangular frame pivotally connected at its lower ends to and extending transversely between the push frame assembly and each blade substantially in alignment with the arch frame, and a fluid pressure actuated power cylinder connected between the apex of each triangular frame and the arch frame to swing the former up or down.

4. A check forming machine comprising a push frame assembly yoke-like at the rear end for straddling a tractor from the front and including a forwardly projecting frame portion, an elongated V-shaped earth working blade structure including separate blades extending rearwardly from its apex on opposite sides of the push frame assembly, means pivotally connecting the front ends of the blades to said forwardly projecting portion for vertical adjustment of said blades, a plurality of longitudinally spaced, vertically swingable transverse stay bars pivotally connected between the blades and the push frame assembly, an arch frame upstanding from the push frame assembly adjacent its rear end, an upstanding, generally triangular frame pivotally connected at its lower ends to and extending transversely between the push frame assembly and each blade substantially in alignment with the arch frame, and a fluid pressure actuated power cylinder connected between the apex of each triangular frame and the arch frame to swing the former up or down; the push frame assembly being vertically adjustable relative to the tractor.

5. A check forming machine comprising a push frame, such push frame including a substantially U-shaped yoke adapted to be horizontally disposed in straddling relation to a tractor from the front, means at the free ends of the yoke for pivoting the same to the tractor, a substantially inverted U-shaped arch frame adapted to arch over the tractor and having its ends secured to the free ends of the horizontal yoke, a push beam

connected with the closed end of the yoke substantially midway between its ends and projecting a substantial distance outwardly therefrom, diagonal brace elements connected to the outer corners of the yoke and to said beam intermediate the ends of the latter, a pair of scraper blades, each blade being pivoted to the outer end of the beam on a horizontal axis extending longitudinally of the beam, said blades diverging from said pivot points in V-formation one to each side of the push beam and push frame, respectively, and in transversely spaced relation with respect thereto, a plurality of longitudinally spaced stay bars projecting laterally out from and being pivoted to the sides of the diagonal brace elements and push frame for vertical swinging movement with respect thereto, the blades being supported on the outer ends of said stay bars, and means interposed between the arch frame and the blades and operative to swing the latter vertically with respect to the push beam and push frame.

6. A machine as in claim 5 in which said last named means includes two triangular frames each pivoted at one lower corner to the arch frame adjacent the lower end of one side of the frame and projecting laterally out therefrom and being linked at its other lower corner to one of the blades, and power means operative to swing the triangular frames on their pivotal connections with the arch frame.

7. A machine as in claim 6 in which the power means includes two hydraulic rams each pivoted at one end to the arch frame and at the other end to the upper corner of one of the triangular frames, and means for admitting fluid under pressure to operate said rams.
